UNITED STATES PATENT OFFICE

2,501,125

SAW SETTER

Carther C. Herring, Montgomery, Ala.

Application October 4, 1948, Serial No. 52,690

1 Claim. (Cl. 76—66)

1

The present invention relates to new and useful improvements in saw sets, and more particularly to a device of this character adapted for setting the teeth of saws and embodying means for setting the teeth at opposite sides of the saw.

It is the cardinal object of the invention to provide a saw tooth setting device which will insure a perfect set of the teeth of a saw, regardless of the thickness of a saw tooth, and the invention embodies the provision of pins adapted for use at the respective sides of the saw and adapted upon delivery of an impact to the pins to set the teeth at a desired angle.

A further object of the invention is to provide a device of this character of simple and practical construction, which is efficient and reliable in use, relatively inexpensive to manufacture, strong and durable, and otherwise well adapted for the purposes for which the same is intended.

Still a further object of the present invention is the provision of a device of the character described whose pins have head portions specifically designed for the setting of several teeth simultaneously, and said pins being interchangeable with pins having differently formed head portions, so that my new and improved device can be used also for punching, crimping and other sheet metal work.

With the foregoing and other objects in view which will appear as the description proceeds, the invention consist of certain novel details of construction and combinations of parts hereinafter more fully described and pointed out in the claim, it being understood that changes may be made in the construction and arrangement of parts without departing from the spirit of the invention as claimed.

In the accompanying drawings the preferred forms of the invention have been shown.

In said drawings:

Figure 1 is a top plan view of a preferred embodiment of my invention with the top portion fractionally broken away;

Fig. 2 is a sectional view on the line 2—2 of Fig. 1;

Fig. 3 is a sectional view on the line 3—3 of Fig. 1;

Fig. 4 is a detailed side view of a pair of pins for sheet metal work;

Fig. 5 is a front view of one of the pins of Fig. 4;

Fig. 6 is a detailed side view of a pair of punching pins;

Fig. 7 is a front view of one of the pushing pins of Fig. 6;

2

Fig. 8 is a detailed view of another pair of pins for sheet metal work; and

Fig. 9 is a front view of one of the pins of Fig. 8.

5 Similar reference characters refer to similar parts throughout the several views.

In the drawing the numeral 1 denotes a casing from one of whose side walls extends a stationary handle 2, which preferably is formed as a unit with the casing 1, and whose top wall has a reinforced perforated center portion 40 that is formed as a groove extending crosswise through the lower portion of the casing. A normally vertical lever 4 which is extended into the casing 1 through the perforated top portion 3 is tiltably secured thereto by means of a cross pin 5, which extends through the lever 4 and is extended at both ends into the casing 1 (Figs. 2 and 3). The portion 6 of the lever 5, which extends into the top portion 3 as well as into the casing 1, preferably is bifurcated, and connecting rods 9 and 10 are linked to the end sections of the bifurcated portion 6 by means of pins 7 and 8 respectively. The upper extremities of the vertical portions 25 of a plurality of angular members 13 are connected to the outer extremities of the rods 9 and 10 respectively by means of shafts 42 extended therethrough, and the members 13 are pivoted at both sides of the lever 4 to lug portions 19 of the casing 1 by means of shafts 41 (Fig. 2). The lower parts 14 of the casing at both sides of the groove 40 are detachably secured to the casing 1 by means of screws 21, which extend through the parts 14 and engage internally threaded bores in the lug portions 22 of the casing 1 (Figs. 1 and 2). The parts 1 and 14 are provided with upwardly extending registering panel portions 18, and a plurality of horizontal pins 15, which register with the horizontal portions 40 of the angular members 13, are slidably extended through the panel portions 18 as well as through the vertical wall sections of the U-shaped bottom portion 40. Those portions of the pins 15 which extend into the grooved U-shaped bottom portion 40 are formed as heads 16, which have serrated face sections adapted for engaging the teeth of a saw. A spring 17 is interposed between the outer vertical wall section of the grooved U-shaped bottom portion 40 and a washer 43, or a cross-pin or the like, which is secured to each pin 15. The springs 17 tend to force the pin heads 16 away from the center of the U-shaped groove 40 upon releasing the lever 4. If the latter is tilted, the parts 7 to 10 and 55 13 force the pins 15 and their heads 16 toward

the center of the U-shaped groove 40, so that the heads 16 act upon the teeth of a saw. The latter is indicated by dash-and-dotted lines and denoted by the numeral 44 in Figs. 1 and 2. In order to steady the setter on the saw 44, and to prevent bending of the latter, I prefer to extend the lower lateral end portions 23 of the part 14 beneath its lower edge 20, and to provide in the end portions 23 threaded bores into which are screwed bolts 45. One extremity of each bolt 45 is provided with a slot 46 (Fig. 2) adapted for being engaged by a screw driver (not shown), while the opposite extremity of each bolt 45 is provided with a head 24, which preferably is shaped semi-spherical, or oval, or which is of 15 any other suitable shape and is adapted for laterally engaging the blade of a saw 44, inserted into the groove 40.

While the pins 15 with their heads 16 are adapted for the setting of saw teeth, said pins 15 can be removed from the device after disconnecting the parts 14 from the casing 1, and other pins with differently shaped head portions can be substituted for the pins 15. For instance, pairs of pins 27 having heads 25 as shown in Figs. 4 and 5 can be used as so-called "hand breaks" for sheet metal work; or pairs of punch pins as shown in Figs. 6 and 7, each pair consisting of a pin 31 having a head 23 with a bore 39 and another pin 26 having a head 29; or pairs of crimper pins as shown in Figs. 8 and 9, each pair consisting of a pin 34 having a V-shaped female head 32 and of a pin 35 having a male head 33 can be used.

Since certain changes may be made in the above article and different embodiments of the invention could be made without departing from the scope thereof, it is intended that all matter contained in the above description or shown in the accompanying drawing shall be interpreted as 35 illustrative and not in a limiting sense.

It is also to be understood that the following claim is intended to cover all of the generic and specific features of the invention herein described, and all statements of the scope of the 45

invention which as a matter of language might be said to fall therebetween.

Having thus fully described my said invention, what I claim as new and desire to secure by 5 Letters Patent is:

A device of the character described comprising 10 a casing whose top wall has a perforated center portion and whose bottom has an upwardly extending U-shaped center portion forming a groove which extends through the lower portion of the casing, a stationary handle being laterally extended from one of the side walls of 15 said casing, a normally upright lever extended into said casing through the perforated top of said casing being tiltably secured to the latter, a plurality of horizontal movable pins extending from opposite directions through the vertical wall portions of said groove, resilient means attached to 20 said pins for forcing them away from the center of said groove, angular members whose horizontal extremities register with the extremities of 25 said pins being pivotably secured to said casing within the latter, connecting rods being hinged with one of their ends to the vertical portions of 30 said angular members and with the other one of their ends to said lever, and lengthwise adjustable bolts extending into said groove being provided at the lateral extremities of said casing, those portions of said pins which extend into said groove being formed as heads, and said pins being interchangeable with pins having differently formed head portions, all substantially as described.

CARTHER C. HERRING.
